UNITED STATES PATENT OFFICE.

FRANK L. O. WADSWORTH, OF PITTSBURGH, PENNSYLVANIA, ASSIGNOR TO THE SPIRELLA COMPANY, OF MEADVILLE, PENNSYLVANIA, A CORPORATION OF PENNSYLVANIA.

GARMENT-STAY.

1,212,856.

Specification of Letters Patent. Patented Jan. 16, 1917.

Application filed July 21, 1914. Serial No. 852,256.

To all whom it may concern:

Be it known that I, FRANK L. O. WADSWORTH, a resident of Pittsburgh, in the county of Allegheny and State of Pennsylvania, have invented a new and useful Improvement in Garment-Stays, of which the following is a specification.

This invention relates to wire garment stays, and particularly to stays for use in 10 corsets and like articles of wearing apparel.

The object of the invention is to provide a stay for this purpose which can be easily fabricated, which is very flexible and resilient in all directions, which includes a long 15 length of wire for a stay of given dimensions, and one in which the opposite edges of the stay are strongly reinforced so that successive portions of the stay mutually brace each other and prevent the liability 20 of short bends, thereby securing both durability of the stay and comfort to the user.

The invention comprises a stay constructed as hereinafter described and claimed.

In the drawings, which illustrate several 25 embodiments of the invention, Figure 1 is a face view of one form of stay; Fig. 2 is an edge view thereof; and Figs. 3, 4 and 5 are views corresponding to Fig. 1 and illustrating modifications.

The stay is formed of wire, and in the 30 embodiments illustrated in the drawings is formed of a single wire 1, which is bent back and forth across the stay alternately from edge to edge thereof to form a series 35 of transversely extending portions or crossings 2 and two rows of open loops 3 lying along the edges of the stay. The transverse or crossing portions of the wire are substantially straight and parallel to each other and may extend substantially at right 40 angles to the length of the stay, as shown in Figs. 1, 3 and 4, or may extend at an angle to a true transverse line, as shown in Fig. 5. The several crossings extend from 45 one edge of the stay to a point short of the other edge, each crossing merging into an extension 4 of a loop on the other edge of the stay, successive crossings merging into 50 edge loops at opposite edges of the stay. The extended loops 4 project toward one end of the stay and at an angle to the main portions of the loops. When the crossing portions of the wire lie in substantially true

transverse lines, as shown in Figs. 1, 3 and 55 4, the extended loops 4 lie substantially at right angles to the crossings, while when the crossing portions of the wire are at an angle to a true transverse line the extended loops 4 along opposite edges of the stay lie respectively at obtuse and acute angles to the crossing portions of the wire, as shown in Fig. 5.

Each of the extended loops 4 preferably 60 overlaps the next additional crossing portion 65 of the wire, as shown at 5 in Fig. 1, but may overlap said crossing to any desired amount, the stay shown in Fig. 3 showing a greater overlap than that shown in Fig. 1. If desired, each extended loop 4 may extend toward one end of the stay to such an amount that it overlaps the second adjacent crossing portion of the wire, as indicated at 6, Fig. 4, and to increase the resistance of the stay to 70 flexure the end portion of the extended 75 loop 4 may be somewhat enlarged laterally, so that it materially overlaps the second adjacent crossing, as indicated at 7.

This stay is very readily fabricated, as 75 the loops may be formed along lines extending transversely of or at an angle to the length of the stay, as shown in dotted lines at 8, Fig. 4, and may then be bent inwardly 80 toward the center line of the stay so that the wire forming the outer portions of the loops 85 lies in longitudinal lines and produces substantially straight side edges of the stay.

The two rows of overlapping loops along 90 the edges of the stay reinforce the same against bending stresses and mutually brace the several loops upon each other, so that the stay is not so liable to take a permanent set when subjected to short bends. Also, the arrangement includes a long length of wire 95 and a fairly close network in a stay of given dimensions.

The stay described is simple, can be 100 readily manufactured, is strong, resilient and flexible, and avoids the concentration of wear at local points, so that crystallization and breakage of wire is prevented.

What I claim is:

1. A garment stay, comprising wire bent 105 back and forth across the stay to form two series of loops lying along the edges of the stay, each edge loop overlapping the next crossing portion and comprising two paral-

parallel portions of the wire extending longitudinally of the stay and joined by a curved end portion, and a series of transversely extending parallel crossing portions connecting successive loops on opposite edges of the stay.

2. A garment stay, comprising wire bent back and forth across the stay to form two series of loops lying along the edges of the stay, each edge loop overlapping the next crossing portion and comprising two parallel portions of the wire extending longitudinally of the stay and joined by a curved end portion, and a series of transversely extending parallel crossing portions, each of said crossing portions extending from the inner of the two longitudinal wire portions of one edge loop to the outer wire portion of the next adjacent edge loop on the other edge of the stay.

3. A garment stay, comprising wire bent back and forth across the stay to form two series of loops lying along the edges of the stay, each edge loop comprising two parallel portions of the wire extending longitudinally of the stay and joined by a curved end portion, and a series of transversely extend-

ing parallel crossing portions connecting successive loops on opposite edges of the stay, each of said edge loops overlapping a plurality of the next adjacent crossing portions of the wire.

4. A garment stay, comprising wire bent back and forth across the stay to form two series of loops lying along the edges of the stay, each edge loop comprising two parallel portions of the wire extending longitudinally of the stay and joined by a curved end portion, and a series of transversely extending parallel crossing portions, each of said crossing portions extending from the inner of the two longitudinal wire portions of one edge loop to the outer wire portion of the next adjacent edge loop on the other edge of the stay, each of said edge loops overlapping a plurality of the next adjacent crossing portions of the wire.

In testimony whereof I have hereunto set my hand.

FRANK L. O. WADSWORTH.
